UNITED STATES PATENT OFFICE.

HENRY F. BECHMAN, OF BATTLE CREEK, MICHIGAN, ASSIGNOR TO EDWIN C. NICHOLS, OF SAME PLACE.

PAPER FOLDER AND PASTER.

SPECIFICATION forming part of Letters Patent No. 656,924, dated August 28, 1900.

Application filed December 20, 1899. Serial No. 740,996. (No model.)

To all whom it may concern:

Be it known that I, HENRY F. BECHMAN, of Battle Creek, in the county of Calhoun and State of Michigan, have invented certain new and useful Improvements in Paper Folders and Pasters; and I hereby declare that the following is a full, clear, and exact description thereof, reference being had to the accompanying drawings, which form part of this specification.

This invention is an improvement in machinery for folding and pasting webs of paper, especially adapted for use in connection with web-printing machines, and particularly designed for use in connection with the well-known Cox duplex web-printing machines when the same are arranged to print papers of more than eight pages and up to sixteen-page papers, each page being half the regular size which the machine is designed to print.

The invention, in brief, is a novel combination of pasting mechanism, with a folder of the "angle-bar" or "cow-catcher" type.

With the old style of tape and tucker-bar folders it is an easy matter to paste a sixteen-page paper, as the paste can be applied after the web is severed into sheets and partly in the direction in which the webs are running; but with an angle-bar folder the paste must be applied transversely of the web before it is severed, and it is necessary to apply the paste at two different points and at different times—first, one application must be made on one web before it has passed the former, and the second application must be made after the webs have passed the former and been thereby folded to page widths, and, further, this second application of paste must be made to the partly-folded webs between the folds thereof and transverse to the direction in which they are running. On account of these difficulties in applying the paste it has heretofore been impossible to print and paste a sixteen-page paper on a Cox duplex press with angle-bar folder. By my present invention these difficulties are overcome and I am enabled to employ a cow-catcher or angle-bar folder and yet completely paste the papers by the employment of two pasting mechanisms, one of which applies the paste transversely to one of the webs (or one-

half of the previously-split web) before they reach the "folder-former," and the other of which is arranged to apply the paste to an interior fold of the webs after they pass the point of the former, in order to do which the web is preferably slotted near the point of the former, and after the folded and slotted webs have left the former the folds thereof are separated and one division is led past the second pasting mechanism, by which the paste is applied to the separated fold transversely of the run thereof, and then the separated folds are reunited and passed through the cutting mechanism, by which the webs are finally severed into sheet lengths, as newspapers, &c. Another advantage obtained by the present invention is that the slitting of the webs at the point of the former results in the upper edges of the sheets of the complete paper being entirely cut or separated, thus leaving all pages properly free and open, while yet securely pasted at the back margin.

The accompanying drawings illustrate a practical form of apparatus embodying the invention, showing an angle-bar folding and pasting mechanism for a sixteen-page paper, particularly adapted to the improved Cox duplex press, but of course applicable to other printing-machines.

In said drawings, Figure 1 is a vertical longitudinal section through the folding and pasting mechanisms of the machine, and Fig. 2 is a transverse vertical sectional elevation of the same.

In said drawings, B designates the former of an angle-bar or cow-catcher folder, below which is a pair of coacting rolls E E', by which the web is drawn over the former, and to one side thereof is a pair of cutting-cylinders I I', parallel with the rolls E E' and through which the webs are finally led and by which they are severed into sheet lengths. These parts are of ordinary construction and need no other specific explanation herein.

The invention may be employed in machines wherein two separate webs are printed and assembled at the folder, or it can be employed in machines wherein one extra-wide web is printed, which is thereafter split longitudinally before it reaches the former, one

half of such web being carried over angle-bars and superimposed over the other half before reaching the former. Then the assembled halves of the doubled web are slit by the 5 slitters in the former, as hereinafter described. For convenience in explanation I refer to two webs, meaning thereby either originally-separate webs or the longitudinally opposite and separate halves of an originally- 10 single wide web.

At the top of the former is a pair of web-guide rollers C and D, arranged one slightly above the other, and one web W is led from the printing mechanism (not shown) over the 15 roller D and down over the former to and between rolls E E', and another web w is led from the printing mechanism (not shown) to and under a guide c, up to and over the roller C, and thence down over the former to the 20 rolls E E', as shown, the webs W and w meeting each other at the top of the former and passing down over the latter, being folded together longitudinally by the former and rolls E E' in the usual manner. Prior 25 to passing between the rolls E E', however, the webs are slit longitudinally by a suitable mechanism located near the point of the former. As shown, this slitting mechanism consists of a pair of shear-acting cutter-disks M and M', disk M being mounted 30 upon a shaft M², behind the point of the former and disk M' upon a shaft M³, above or exterior to the point of the former, which is slotted, as shown at b, to permit coaction of 35 these disks. Shaft M² may be driven by gears M⁴ and M⁵ from a shaft M⁸, suitably journaled in a bracket attached to the former, and shaft M⁸ may be driven by a sprocket M⁹ and chain M¹¹ from a sprocket M¹³ on a shaft M¹⁴, driven 40 by gears M¹⁵ and M¹⁶ from a gear M¹⁷ on the driving or power shaft F, as shown. The shaft M³ of disk M' preferably has both a rotary and a longitudinal movement in its bearing in bracket M⁵ and may be driven by a 45 sprocket M¹⁰ and chain M¹² from another sprocket M¹³ on said shaft M¹⁴, as indicated in the drawings. A spring N is interposed between a shoulder on bracket M⁵ and a collar or washer N' on shaft M³ between the hub 50 of disk M' and bracket M⁵. This spring keeps the disk M' always laterally in contact with the disk M, so that these disks will shear-cut the web. The folds of the slit webs after 55 passing between rolls E are divided, half of both webs W and w being led down under a rollers K and thence directly up to and between the cutting-cylinders I I', and the other halves of webs W and w being led over guide-rollerz K' K² back to roller K, where they are 60 reassembled with the other portions of the webs W w and led therewith through the cutting-cylinders I I'. The object of thus separating the folds of the webs is to enable the second pasting operation to be advantageously performed.

I shall now describe the pasting mechanisms.

The first pasting mechanism is located between rolls c and C and is adapted to apply paste to the face of web w, transversely thereof. As shown, a "wing-paster" H is employed, the wing being mounted on a shaft G³, which may be rotated by a train of gears G' from a gear G on shaft F, as indicated in the drawings. The paster H receives paste from a 75 roller G⁴, which rotates against the periphery of a roller G⁵ in the paste-pot G⁶, as shown. The guide-roller c may be driven by or from one of the intermediate gears G', as indicated in the drawings. The second pasting mechanism is located in the loop formed in the separated folds of the split webs between the rolls E E' and K and is adapted to apply the paste transversely to the folds, as indicated. As shown, the second paster is also a wing-paster H² and is mounted on a shaft 16, located intermediate the guide-rollers K' and K², so as to be inclosed within the loop of the web between the roll E' and roller K. Paster H² is supplied with paste by a roll J' from the 80 pot J, as shown in Fig. 2. The shaft 16 may be provided with a large gear 15 and driven by a train of intermediate gears 14 from a gear on the shaft of the cutting-cylinder I, and the guide-rollers K' K² may be driven 85 from gear 15 by intermediates 17, as shown. The shaft of the cutting-cylinder I may be driven by bevel-gears 12 13 from shaft F, as shown. The rolls E E' are provided with intermeshing gears and may be driven from or 90 by one of the intermediates 14. The arrangements of gearing for driving the several parts may be varied to suit the constructor, it only being necessary that the parts shall be driven at the desired relative speeds and in proper 95 relative time.

Operation: The webs W w coming from the printing mechanisms are assembled as they pass over the former B; but before they come together the paster H applies a line of paste 100 to the margins of web W and transversely of the web, so that as these webs come down over the former they are pasted together transversely. The webs thus pasted together are slit longitudinally as they pass the former 110 and before they enter between the rolls E E', through which at least four thicknesses of paper pass. After passing between these rolls the folds of the slit and pasted webs are separated, those folds of the web which 115 passed over the left-hand edge of the former being led directly under roll K and thence to the cutting-cylinders, while those folds of the web which passed over the right-hand edge of the former are led up over roller K', down 120 under roller K², then back to the roller K, and then to the cutting-cylinders, the latter 125 folds being thus looped around the second pasting mechanism, by which a second line of paste is applied transversely to the separated portion of the web at the point L, intermediate the rollers K² and K. The separated folds 130 of the webs are again reunited at roller K prior to passing between the cutting-cylinders.

ders, so that the final pasting operation is completed before the webs reach the cutting-cylinders. Thus the four thicknesses of the webs will be securely and properly pasted together, and as they pass through the cutting-cylinders the webs are severed into sheet lengths, the sheets being all pasted together, however, so that the machine will deliver sixteen-page newspapers, for example, all properly pasted and folded. Thus by the present invention I am enabled to apply the paste to the web transversely thereof and transversely to the line of movement thereof both before and after the webs pass the former, thus enabling me to employ an angle-bar or cow-catcher folder, and by slitting the web, as described, I obtain the further advantage of freeing all the sheets, so that no subsequent cutting or trimming of the papers will be necessary to free the top edges of the sheets.

Practically one of the rolls K K' K² (preferably one of the latter) may be made laterally adjustable, so that the proper register of the margins can be maintained when the separated folds of the web are again reunited after the second pasting operation.

The feature of splitting webs longitudinally, separating the split portions, applying paste thereto while separated, and subsequently reuniting such portions and cutting them into sheet lengths might be usefully employed in connection with single webs.

That the practical applications of the invention are numerous will be readily comprehended by those skilled in the art, and for the essential features and combinations thereof, for which protection is desired, reference is had to the following claims.

Having thus described my invention, what I therefore claim as new, and desire to secure by Letters Patent thereon, is—

1. The combination of means for assembling two webs and folding the same longitudinally; and means for applying paste transversely to one of the webs before the same are assembled and folded; with means for applying paste a second time to the webs and transversely thereof after the webs have received their first fold, and means for there-

50 after severing the webs, substantially as described.

2. In web folding and pasting mechanism, the combination of means for assembling two webs and folding the same longitudinally, and means for thereafter severing the webs into sheet lengths; with means for applying paste transversely to one of the webs before the same are assembled and folded, and means for applying paste to an inner fold of the webs

55 after the same have received their first fold and prior to the severance thereof substantially as described.

3. The combination of mechanism for assembling and folding webs longitudinally and means for applying paste to the webs prior to the assembling and folding thereof; with means for separating the folds of the webs;

means for applying a line of paste to one of the separated folds and means for reuniting the separated folds.

4. The combination of mechanism for assembling and folding webs longitudinally, means for applying a line of paste transversely to one of the webs prior to the assembling and folding thereof; with means for separating the folds of the webs after they have been folded, means for applying a line of paste to one of the separated folds transversely thereof, and means for reuniting the separated folds and severing the same into sheet lengths, substantially as described.

5. In a web folding and pasting mechanism, the combination of means for assembling two webs and folding the same longitudinally, and means for thereafter severing the webs into sheet lengths; with means for applying a line of paste to one of the webs transversely to the direction of movement thereof and prior to the assembling and folding of the webs, means for separating the folds of the webs after they have been folded to page widths and means for applying a line of paste to one of the separated folds of the web transversely to the line of movement thereof, and means for reuniting the separated folds prior to the severance of the webs, substantially as described.

6. In a web folding and pasting mechanism, the combination of means for imparting a longitudinal fold to a web, means for splitting the web longitudinally after it is folded, and means for separating the divided portions of the web, mechanism for applying paste transversely to one of the divided portions of the web, means for subsequently reuniting the divided portions of the web, and mechanism for thereafter cutting the same into sheet lengths, substantially as described.

7. The combination of means for assembling and imparting a longitudinal fold to webs of paper, means for separating the folds of the web and mechanism for applying a line of paste to the separated folds of the webs, and means for thereafter reuniting the separated folds of the webs, substantially as described.

8. The combination of means for assembling and imparting a longitudinal fold to webs of paper, mechanism for separating the longitudinal folds of the webs, means for applying a line of paste to one of the separated folds of the webs transversely to the length or line of movement thereof, means for reuniting the separated folds of the webs, and means for severing the same into sheet lengths, substantially as described.

9. In web folding and pasting mechanism, the combination of means for assembling and imparting a longitudinal fold to webs of paper, means for longitudinally splitting the folded webs, means for separating the opposite folds of the split webs, mechanism for applying a line of paste to the separated folds of the web, and means for thereafter reuniting the sepa-

rated folds of the split webs substantially as described.

10. In web folding and pasting mechanism, the combination of means for assembling and imparting a longitudinal fold to webs of paper, means for longitudinally splitting the folded web, means for separating the opposite folds of the split webs, mechanism for applying a line of paste to one of the separated folds of the web transversely to the length thereof, and means for thereafter reuniting the separated folds of the split webs, and means for severing the same into sheet lengths, substantially as described.

15. 11. In web folding and pasting mechanism, the combination of means for assembling two webs and folding the same longitudinally, means for longitudinally splitting the folded webs, and means for thereafter severing the webs into sheet lengths; with means for applying paste to one of the webs before the same are assembled and folded, means for separating the opposite folds of the split webs, and means for applying paste to a fold of the 25 web while separated and prior to the severance of the webs into sheet lengths, and means for reuniting the separated webs, substantially as described.

12. The combination of the former and a 30 pair of rolls coacting therewith, means for directing a pair of webs to said former, mechanism for applying paste to one of the webs prior to its passage over the former, mechanism for slitting the folded webs longitudinally, 35 means for dividing or separating the folds of the slitted web, means for applying paste to one portion of the slitted and separated webs, and cutting-cylinders for severing the re-united portions of the webs into sheet lengths, 40 substantially as described.

13. In web folding and pasting mechanism, the combination of means for assembling two webs and folding the same longitudinally, means for longitudinally splitting the folded webs, and means for thereafter severing the webs into sheet lengths; with means for applying paste transversely to one of the webs before the same are assembled and folded, means for separating the opposite folds of the 45 split webs, and means for applying paste to the inner fold of the webs and transversely to the length thereof while separated, after the same have received their first fold, and prior to the severance of the webs into sheet 50 lengths, substantially as described.

14. The combination of the former and a pair of rolls coacting therewith, means for directing a pair of webs to said former, a pasting mechanism for applying paste to one of the webs prior to its passage over the former, mechanism for slitting the folded webs longitudinally, a second pasting mechanism, guide-rollers by which one half of the slitted web is led around the second pasting mechanism, 65 means for reuniting the separated webs, and cutting-cylinders between which the reunited slitted portions of the webs are led and sev-

ered into sheet lengths, substantially as described.

15. The combination of the former, the 70 rolls at the apex thereof and coacting therewith, cutting-cylinders at one side of the former, a pasting mechanism at the opposite side of the former, mechanism for slitting the folded web, means for directing one portion of the slitted web directly to the cutting-cylinders, and means for directing the other portion of the slitted web past the paster and thence to the cutting-cylinders, substantially as described.

16. The combination of the former, the rolls at the apex thereof and coacting therewith, a secondary pasting mechanism beside the former, means for directing a pair of webs to and over the former, a primary pasting 85 mechanism adapted to apply paste to the webs before they reach the former, mechanism for slitting the folded webs, means for directing one portion of the slitted webs directly to the cutting-cylinders and for directing the other portion of the slitted webs past the secondary pasting mechanism, substantially as described.

17. The combination of the former, the rolls at the apex thereof and coacting therewith, cutting-cylinders at one side of the former, a secondary pasting mechanism at the opposite side of the former, means for directing a pair of webs to the former, and mechanism for applying a line of paste to one of the webs transversely to the line of movement thereof before it reaches the former; with mechanism for slitting the folded web, means for directing one portion of the slitted web directly to the cutting-cylinders and for directing the other portion of the slitted web past the secondary pasting mechanism and thence to the cutting-cylinders, substantially as described.

18. The combination of the former, the 110 rolls at the apex thereof and coacting therewith, cutting-cylinders at one side of the former, and a secondary transversely-operating pasting mechanism at the opposite side of the former, means for directing a pair of 115 webs to the former, and mechanism for applying a line of paste to one of the webs transversely to the line of movement thereof before it reaches the former, and means at the apex of the former for slitting the web 120 longitudinally; with means for directing one portion of the slitted web directly to the cutting-cylinders and a set of guide-rollers for looping the other portion of the slitted web around the secondary pasting mechanism and thence to the cutting-cylinders, all substantially as and for the purpose set forth.

In testimony that I claim the foregoing as my own I affix my signature in presence of two witnesses.

HENRY F. BECHMAN.
